CLAIM

An ornamental design for the vacuum generating device, as shown and described.

DESCRIPTION

FIG. 1 shows a left top front perspective view of the vacuum generating device in accordance with the invention;

FIG. 2 shows a front elevational view thereof;

FIG. 3 shows a right side elevational view thereof;

FIG. 4 shows a rear elevational view thereof;

FIG. 5 shows a left side elevational view thereof;

FIG. 6 shows a top plan view thereof; and,

FIG. 7 shows a bottom plan view thereof.

Any broken lines in the drawings disclose elements which form no part of the claimed design.
